UNITED STATES PATENT OFFICE.

PAUL M. RAINY, OF GLEN RIDGE, NEW JERSEY, ASSIGNOR TO WESTERN ELECTRIC COMPANY, INCORPORATED, OF NEW YORK, N. Y., A CORPORATION OF NEW YORK.

PRINTING-TELEGRAPH SYSTEM.

Application filed December 30, 1921. Serial No. 525,987.

To all whom it may concern:

Be it known that I, PAUL M. RAINY, a citizen of the United States, residing at Glen Ridge, in the county of Essex, State of New Jersey, have invented certain new and useful Improvements in Printing-Telegraph Systems, of which the following is a full, clear, concise, and exact description.

10 This invention relates to printing telegraph systems, and particularly to switching mechanism whereby the operation of systems in which a plurality of sets of printing telegraph apparatus located at one station may be facilitated.

An object of the invention is to provide in a printing telegraph system having a plurality of sets of printing telegraph apparatus located at one station, switching means whereby the transmitting and receiving mechanisms of each set may be operated independently of the corresponding mechanisms of the other set.

Another object is the provision in a system of the above character of switching means whereby the transmitting mechanism of one set and the receiving mechanism of the other set may be operated.

Another object is to provide in a printing telegraph system having a plurality of sets of printing telegraph apparatus located at one station, switching means whereby the recorder of one set may be operated in conjunction with the receiving distributor of the other set.

It is customary practice in offices provided with printing telegraph apparatus to have spare or duplicate sets to insure continued service of the system, should one of the sets fail. Each set is equipped with transmitting and receiving distributors, automatic or keyboard transmitters, and receiving printers, all of which are mounted on separate tables which accommodate but a single operator at a time, and consequently do not permit the simultaneous observance of the operation of the transmitting and receiving mechanisms by separate operators. To obviate such conditions, the present invention provides, in a printing telegraph system comprising two operating tables, each equipped with complete transmitting and receiving mechanisms located at the station and connected by a line con-

ductor equipped for duplex operation, 55 switching means whereby the equipment of each table may be operated in various combinations. For example, the transmitter and transmitting distributor of one set and the receiving mechanism and receiving distributor of the other set may be operated together, the receiving printer individual to one table may under different conditions be controlled by the receiving distributor of the other table, or the equipment of each of 60 the tables may be operated independently.

In the drawing, there is shown a line conductor 6 provided for duplex service extending to a distant station where apparatus similar to that shown in the drawing 70 is located. Attached to the line 6 are transmitting distributors 7 and 8 and receiving distributors 9 and 10. The former distributors connect the transmitting mechanism with the line, while the latter connect 75 the recording mechanism thereto. The distributors 7 and 9 together with their associated mechanisms form a complete set A, while the other distributors 8 and 10 form a second set B, each of which may be 80 operated separately, the transmitting distributor of one set and the receiving distributor of another set with its corresponding printer operated, or the receiving printer of either set may be operated in 85 conjunction with the receiving distributor of the other set.

The transmitting apparatus comprises current control means 11 which, in the preferred form of the invention is a tape transmitter, though, obviously, a keyboard transmitter may be substituted in its place. The transmitter 11 includes a series of contacts 12, 13, 14, 15 and 16 which are arranged to be selectively actuated by selectively operated members controlled by perforations in the transmitting tape (not shown). In order that the transmitting tape may be advanced to bring the next succeeding group of perforations in alignment with the contacts 12 to 16 inclusive, an electromagnet 17 is arranged to be operated upon each revolution of the brush arm of the transmitting distributor 7 for accomplishing this result, as will be more clearly described 100 hereinafter. Associated with the contacts 12 to 16 inclusive, is a plurality of signal storing relays 18, 19, 20, 21 and 22 which are

provided for storing the impulses in accordance with the operation of the selected contacts. Each of these relays has two windings, one of which serves to initially energize the relay while the other serves to maintain the relay energized after their contacts have been closed. Each relay is also provided with two armatures, one for extending circuits to the segments of the transmitting distributor 7 and the other serving to complete locking circuits therefor.

The recording mechanism 23 provides a series of selecting magnets 24, 25, 26, 27 and 28 which have their windings connected with the various segments forming a part of the outer ring of the receiving distributor 9. Thus, the windings of these magnets will be successively connected upon the release of the brush arm 29 due to the energization of the release magnet 34 by the front contact of relay 31, the energization of which is under the control of line relay 70 connected to the line conductor 6. The line relay 70 is operated in accordance with the reception of signals transmitted from the distant station and responds to control the operation of the local relay 31 whereby the selecting magnets will be energized in accordance with the impulses received for recording the desired character. A conductor 32 which is shown extending from a contact on switch 33 may be connected with a printing magnet for effecting the printing of a character as determined by the operation of the selecting magnets.

The transmitting distributor comprises a brush arm 35 which is frictionally mounted on a constantly revolving shaft 37 as is well known to those skilled in the art. The arm 35 is held against rotation by means of a release latch under the control of a release magnet 47. Secured to the brush arm 35 is a pair of brushes 38 and 39. The latter of these brushes connects the continuous ring 40 with the segments 41, 42, 43, 44, 45 and 46 to which the upper armatures of the storing relays 18 to 22 inclusive, are connected, while the former bridges the continuous ring with the local segments 52, 53 and 54.

In order that the storing relays will not be operated for storing impulses until the distributor arm 35 has completed its cycle, a relay 56 is provided which is adapted to be energized upon the energization of any one of the storing relays 18 to 22 inclusive. Relay 56, upon being energized, opens at its contacts, the initial energizing circuit of the storing relays which is completed through the selecting contacts of the tape transmitter previously referred to. Upon the passage of the brush 38 over the segment 54, a circuit is completed including the winding of relay 57 with a source of battery. Relay 57 in operating, opens at its contacts, the energiz-

ing circuit of relay 56 as well as the locking circuit of the storing relays. Thus, after this relay is operated and released, the storing relays 18 to 22 inclusive, may then be actuated for storing impulses in accordance with the actuation of the selecting contacts 12 to 16 inclusive.

The reception of impulses is accomplished by providing a line relay 70 responsive only to incoming impulses which is connected in circuit with the line conductor 6 and which controls through its contacts, the energizing circuit of the local relays 31 and 71 individual to the receiving distributors 9 and 10 respectively. This line relay 70 is of the polarized type and is arranged so that its armature remains in the position set until the reception of an impulse which reverses the position of its armature. The front and back contacts of the local relay 31 are connected with segment 58 of the receiving distributor 9 and the winding of the release magnet 34 respectively. The energization of the release magnet 34 is, however, controlled by the brush 72 mounted on the brush arm 29 which, when the brush arm is at rest, bridges the local segments 73 and 74. From this, it is seen that the energization of the release magnet 34 for releasing the arm 29 is controlled through the back contact of the local relay 31, while the energization of the selecting magnets is controlled through the front contact thereof. Thus, if the front contact of this relay is closed at the time the brush 72 is passing over a segment 75 to which the selecting magnet 28 of the printer 23 is connected, this selecting magnet will be energized for effecting the operation of the selecting mechanism controlled thereby. This circuit extends from battery through the left-hand contact of the key 30, front contact of the local relay 31, segment 58 of the receiving distributor 9, brush 72, segment 75, switch member 76 forming a part of the switch 33, contact 77 and the winding of the selecting magnet 28 to ground.

The equipment individual to the distributors 8 and 10 is similar in every respect to that just described. Therefore, further description of this apparatus is considered unnecessary here.

Common to the recorder 23 of the set A and the recorder 78 of the set B is a switch 33 which has a plurality of spring pressed switch members normally tending to assume the position shown in the drawing, and which are adapted to operate oppositely disposed contacts for controlling the completion of the respective circuits extending from the segments of the distributors 9 and 10 to the selecting magnets of the recorders 23 and 78 respectively. With the switch 33 in the position shown in the drawing, the selecting magnets of the recorder 23 are associated with the segments of the receiving distributor 9 and the selecting magnets of the recorder 78 are associated with the segments of the receiving distributor 10.

ing distributor 9 so that when impulses are transmitted over the line conductor 6, the receiving distributor 9 will be operated for transferring to the selecting magnets 24 to 5 28 inclusive, impulses in accordance with those transmitted from the distant station. Similarly, with the switch member 79 in the position shown in the drawing the selecting magnets of the recorder 78 are associated with the distributor 10.

In the preferred form of the invention a five unit code consisting of impulses of current and intervals of no current is employed in the selection of each character. Therefore, in describing the operation of the system, let it be assumed that a signal composed of the following units be transmitted. Current, no current, no current, current and current. When it is desired to operate the system in the above manner, key 81 associated with the set A must be actuated to close its contacts for conditioning an energizing circuit for the start relay 36, the energizing circuit of which is controlled by 20 the engagement of the brush 38 with the local segment 52 and the continuous ring 50. Also at the receiving station, if it is desired to receive the impulses transmitted by the operation of the transmitting distributor 7 on the receiving distributor 9, it is necessary to actuate the lever of the switch 30 so as to close its left-hand contact thereby connecting battery with the armature and front contact of the local relay 31. It is, 25 of course, to be understood that the system is designed for duplex operation, that is, messages may be transmitted over the line conductor 6 in both directions simultaneously. After the key 81 has been actuated, the release control relay 36 will be energized over a circuit extending from battery through the ring 50, brush 38, local segment 52 and the winding of the release control relay 36 and the contact of the switch 81 to ground. Upon the operation 30 of the release control relay 36, an energizing circuit is established for the release magnet 47 extending from battery through the winding of the release magnet 47, armature and alternate contact of relay 36, contact of the switch 81 to ground. The energization of the release magnet 47 withdraws the release latch controlled thereby from engagement with the brush arm 35 thereby 35 permitting this brush arm to be revolved with the continuously revolving shaft 37.

In accordance with the previously mentioned group of selecting units or impulses, contacts 12, 15 and 16 of the transmitter will be closed, thereby completing the energizing circuit for storing relays 18, 21 and 22. These circuits extend from grounded battery, upper winding of these relays, the closed contacts of the transmitter 11, back contacts of relays 56 and 57, front contacts

of release control relay 36 and the contacts of the switch 81 to ground. Storing relays 18, 21 and 22 thereupon close their contacts to extend the circuits controlled by the armatures of these relays to the segments of 70 the transmitting distributor which are subsequently connected through the distributor 8 to the winding of a pole-changing relay 66 for transmitting current impulses over the line conductor 6 representing the desired character. A locking circuit for each of these relays is also established at this time over a circuit extending from grounded battery through the lower winding and armature of each of these relays and the winding of relay 56 and the armature and normal contact of relay 57 to ground. Relay 56 is also energized at this time and attracts its armature for opening the initial energizing circuit of the storing relays 18, 21 75 and 22. The operation of the release magnet 47 as before described, withdraws the latch controlled thereby and permits brush arm 35 to revolve with the shaft 37. The release of the brush arm 35 causes the circuit 80 extending from the battery connected with the winding of the pole-changing relay 66 through the continuous ring 64, brush 63 and segment 62 of the transmitting distributor 8, brush 39, segment 46 and the ring 40 of the transmitting distributor 7 to be broken. This, therefore, opens the energizing circuit of the pole-changing relay 66 and permits the armature controlled thereby to assume a position opposite to that 85 shown in the drawing and consequently applying a polarity of battery opposite to that normally connected with the line conductor 6. Upon the receipt of this initial impulse, the receiving relay 70 which responds only to incoming impulses, reverses the position of its armature and causes the disconnection of the source of battery from the winding of the local relay 31, thereby 90 causing the release of this relay. As previously described, switch 30 is actuated in a manner to close its left-hand contact. Thus, upon the release of the relay 31 and the closure of this back contact, an energizing circuit is established for the release 95 magnet 34 of the receiving distributor 9. This circuit extends from battery through the left-hand contact of switch 30, back contact of relay 31, winding of release magnet 34, segment 74, brush 72 carried by the brush arm 29 and the segment 73 to ground. Release magnet 34, in operating, withdraws the release latch controlled thereby for permitting the arm 29 to revolve.

The passage of the brush 38 of the transmitting distributor 7 over segment 53 completes an energizing circuit for magnet 17 which magnet, in operating causes the operation of suitable mechanism (not shown) to advance the transmitting path for posi- 120 125

tioning the next succeeding group of perforations in alinement with the selecting contacts 12 to 16 inclusive. But inasmuch as relay 56 at this time is energized, the storing relays connected with the actuated contacts will not be energized. Brush 38 in passing off of segment 52 opens the energizing circuit of relay 36 which is thereupon deenergized and opens the energizing circuit of the release magnet for restoring the release latch to normal position for engaging the arm 35 after it has completed one cycle. As the arm 35 revolves, segment 41, to which the upper armature of the storing relay 18 is connected, bridges the continuous ring 40 and since storing relay 18 is energized, an energizing circuit is completed for the pole-changing relay 66. This circuit may be traced from battery connected with the winding of the pole-changing relay 66, conductor 65, segment 64 of the distributor 8, brush 63, segment 62, conductor 60, continuous ring 40 of the transmitting distributor 7, brush 39, segment 41, upper armature and alternate contact of the storing relay 18 to ground. The pole-changing relay 66 is thereupon energized for reversing the position of its armature and applying battery to the line conductor 6, the polarity of which is such as to reverse the position of the armature of the line relay 70, located at the distant station, or to the position shown in the drawing.

At the distant station, the line relay 70, in responding to this impulse, completes the energizing circuit for the local relay 31 which thereupon closes its front contact and connects battery with the segment 58 of the receiving distributor 9 so that upon the passage of the brush 72 over the segment 75, an energizing circuit will be established over the circuit previously described for the selecting magnet 28 of the recorder 23. Selecting magnet 28 will thereupon be energized for positioning the selecting mechanism controlled thereby. Since storing relays 19 and 20 have not been energized, the energizing circuit for the pole-changing relay 66 will be opened upon the passage of the brush 38 over the segments to which the upper armatures of these storing relays are connected. Consequently, the receiving relay 70 at the distant station will be caused to reverse the position of its armature so that the local relay 31 remains deenergized. Thus, upon the passage of the brush 72 over the segments to which the selecting magnets 26 and 27 of the recorder 23 are connected, these magnets will not be energized owing to the position of the armature of the local relay 31. However, when the brush 39 engages segment 44, the energizing circuit for the pole-changing relay 66 will again be completed for causing the transmission of an impulse of a polarity opposite to that

previously transmitted. The operation of the system at the distant station is identical with that previously described in connection with the selection of the selecting magnet 28. The same is true when the brush 39 passes over the segment 45. The selecting magnets at the distant station corresponding with the storing relays will, of course, be operated in the same manner as previously described in connection with that of the selecting magnet 28. 70 75

Just before the brush arm 35 is arrested by the latch under the control of the release magnet 47, segment 54 is bridged with the ring 50 by the brush 38, thereby completing an energizing circuit for relay 57 extending from battery through ring 50, brush 38, segment 54 and the winding of the relay 57 to ground. This relay 57 in energizing opens, at its left-hand contact, the energizing circuit for relay 56 which is thereupon deenergized for again establishing the initial energizing circuit for the storing relays 18 to 22 inclusive. 80 85

Upon the engagement of the brush 39 with the segment 46, an energizing circuit is again established for the pole-changing relay 66 which restores the position of the armature controlled thereby to the position as shown in the drawing thereby causing the energization of the receiving relay at the distant station for likewise completing an energizing circuit for the local relay 31 so that the release magnet 34 will be deenergized just before the arm 29 of the distributor 9 has completed its cycle of rotation. Thus, since the release magnet 34 is now deenergized, the brush arm 29 will be arrested due to its engagement with the release latch controlled by the release magnet 34. 95 100 105

If the switch 33 is actuated to move the switch member 80 to the left, recorder 23 will be disconnected from the segments of the distributor 9 and the selecting magnets of the recorder 23 connected thereto. In this manner, impulses received on the distributor 10 may be transferred and recorded on the recorder 23 individual to the set B. It is, thus, seen that an operator may be stationed to observe the operation of the transmitter and printer without interfering with the work of the other operator. 110 115

If the key 30 is actuated to close its right-hand contact, the distributor 10 will be operated rather than the distributor 9, as previously described. Conditions similar to those described in connection with the operation of the distributor 9 would, therefore, result in the operation of the receiving distributor 10. Also the operation of the receiving distributor 10 may be recorded on the recorder 23 associated with the set A by the proper positioning of the switch member 79 of the switch 33. 120 125 130

What is claimed is:

1. In a printing telegraph system, the combination of a line, a plurality of transmitting distributors and a plurality of receiving distributors cooperating with said line, an impulse responsive relay common to said transmitting distributors, means for causing said relay to respond to selections received from a particular one of said transmitting distributors alone, a plurality of recorders and means for associating any of said recorders with any of said receiving distributors.
2. In a printing telegraph system, the combination of a line, a plurality of transmitting distributors serially connected, means for sending selections to said line utilizing contacts of said plurality of distributors, means for determining the particular distributor to be effective in the sending of selections to said line, a plurality of receiving distributors normally associated in common with said line, means for rendering one alone of said receiving distributors effective to receive selections from said line, a plurality of recorders, and means for associating any one of said recorders with any of said distributors.
3. In a printing telegraph system, the combination with a line, of a plurality of transmitting distributors connected serially, a relay normally associated with said plurality of distributors, said relay being adapt-

ed to directly control the transmission of selecting impulses to said line, means for rendering said relay responsive to but one of said serially connected transmitting distributors, a plurality of receiving distributors associative with said line, a plurality of serially connected start relays each individual to a receiving distributor, means for rendering a particular one of said relays effective to determine the association of a particular one of said receiving distributors with said line, a plurality of recorders, and means for associating any of said recorders with any of said distributors.

4. In a printing telegraph system, the combination with a line, of a plurality of transmitting distributors and a plurality of receiving distributors associative with said line, means for sending selecting impulses to said line utilizing a series circuit through contacts of said plurality of transmitting distributors, means for sending impulses to said line independently of said series circuit, means for associating any of said receiving distributors with said line, a plurality of recorders, and means for associating any of said recorders with any of said receiving distributors.

In witness whereof, I hereunto subscribe my name this 27th day of December A. D., 1921.

PAUL M. RAINES.
